UNITED STATES PATENT OFFICE

2,316,243

TRANSMISSION LINE TOOL

David C. Hubbard, Centralia, Mo., assignor to
 A. B. Chance Company, Centralia, Mo., a corporation of Missouri

Application October 9, 1941, Serial No. 414,223

5 Claims. (Cl. 81—57)

The present invention relates to transmission line tools, and is particularly concerned with the provision of improved types of wrenches adapted to be used in connection with standard sockets for actuating threaded members on the connectors or the pole insulators of high transmission lines.

One of the objects of the invention is the provision of an improved wrench for use on high voltage transmission lines, by means of which nuts or other threaded members on connectors or other devices carried by the line conductors may be driven home or removed while the line is energized, irrespective of the angular position in which the threaded members are located.

Another object of the invention is the provision of a wrench of the class described which is adapted to be used for tightening nuts or removing them or for actuating other threaded members on high voltage transmission lines, and which has provision for exerting a still more powerful effort by locking the rotating mechanism and turning the threaded member directly by revolutionary movement of the handle.

Another object of the invention is the provision of a wrench of the class described which is safe, durable, dependable, adapted to operate without any binding, and adapted to be manufactured at a low cost.

Another object of the invention is the provision of a wrench of the class described which is adapted to be used with its driven end in any of a multiplicity of different angular positions with respect to the driving end so that no matter what position the operator may find himself in, the wrench may be so adjusted as to exert a positive rotative force on a threaded member carried by the line.

Other objects and advantages of the invention will be apparent from the following description and the accompanying drawings, in which similar characters of reference indicate similar parts throughout the several views.

Referring to the drawings, of which there are two sheets,

Fig. 1 is a fragmentary view in perspective of a transmission line, showing an insulator provided with a line clamp secured by bolts and nuts, illustrating the application of the wrench to one of the nuts;

Fig. 2 is a fragmentary view in perspective of the upper end of the tool;

Fig. 3 is a sectional view, taken on the plane passing through the axis of the driving and

driven shafts, with the shafts in elevation, showing the details of construction of the tool;

Fig. 4 is a side elevational view of a modification in which the tool fitting is provided with a universal flange for attachment to a universal pole;

Fig. 5 is a view similar to Fig. 3 of another modification provided with positive means for locking both shafts to the pole;

Fig. 6 is a fragmentary sectional view, taken on the plane of the line 6—6 of Fig. 5;

Fig. 7 is a sectional view, taken on the plane of the line 7—7 of Fig. 5, looking in the direction of the arrows;

Fig. 8 is a sectional view, taken on the plane of the line 8—8 of Fig. 5, looking in the direction of the arrows.

Referring to Figs. 1 to 4, 10 indicates in its entirety the improved line tool, which preferably comprises an elongated insulating pole 11 of wood or other suitable material, and a tool fitting 12 carried by the upper end of the pole. 13 indicates a standard wrench tube of the type having a non-circular socket in each end, such as, for example, a square socket or a hexagonal socket, or the tube 13 may have a hexagonal socket in its lower end and a square socket in its upper end.

14 indicates a line pole insulator, and 15 indicates a metallic guide member carried by the insulator and having a pair of upwardly extending threaded bolts 16 for receiving nuts 17 to draw the clamping member 18 into engagement with the line conductor 19.

The wrench or tool 10 is shown in engagement with the tube 13, the lower end of which engages one of the nuts 17.

Referring to Fig. 3, the wooden pole 11 comprises an elongated wooden member of kiln-dried lumber, preferably protected by insulating varnish and tested for its insulating properties at the voltages at which it is to be used.

The length of the pole 11 depends upon the voltage of the line on which the pole is to be used. At its upper end the pole 11 supports the tool fixture 12, which is preferably provided with a cast metal ferrule 20, having a cylindrical socket 21 adapted to fit on the end of the pole 11.

The walls of the socket 21 may have a close frictional fit with the end of the pole, but it is also preferably secured to the pole by means of a pair of transversely extending metal rivets 22 passing through apertures in the opposed walls of the ferrule 20 and through a registering bore in the pole.

The upper end of the ferrule is closed by a

flat end wall 23, which may support a stub shaft 24. The stub shaft 24 may have its upper end threaded at 25 complementarily to the threads 26 carried in the centrally located bore of a cog wheel 27. The cog wheel 27 is similar in construction to the cog wheel 28, later to be mentioned; and it is of such shape that these cog wheels are adapted to mesh so that one may be driven by the other in any of a plurality of angular positions, varying from the vertical position shown in Fig. 4 to an extreme opposite position where the driven shaft 29 extends downward.

These cog wheels are provided with a circular body portion which preferably tapers toward its lower end 30, and at the upper end the thickness of the body portion increases, and it is provided with a plurality of regularly spaced axially extending teeth 31 separated by the tooth spaces 32.

The teeth 31 preferably taper toward their upper and inner edges, and they are rounded on all sides, and they preferably have a relatively large clearance between the teeth; that is, the grooves are preferably larger than the teeth, as it is of no particular detriment to permit a little lost motion.

As viewed in Fig. 3, it will be seen that the teeth 31 extend radially and longitudinally from the body 27 and that they are substantially lobe shaped and that they project above the upper end surface 33 of the gear 27 and above the upper end 34 of the shaft 24.

The gear 27 may be threaded on the shaft 24 and secured in predetermined position by means of a key 35 secured in a keyway in the shaft and gear. A steel thrust washer 36 is preferably interposed between the gear and the housing member 37.

The housing member 37 may comprise a cast metal member which is formed with a centrally located bore 38 for receiving the cylindrical part of the shaft 24.

The lower part of the housing 37 at 39 may be substantially cylindrical; but it is preferably provided with a lateral extension 40, which may be provided with a bore 41 for receiving the compression spring 42 and ball 43.

The upper end of the housing 37 is of substantially bell shape and adapted to house the gear 27. At one side of the upper end of the housing 37 it is provided with a pair of parallel upwardly projecting ears 44, 45 (Fig. 4), which are provided with the transverse aligned bores 46, the axis of which is preferably located substantially tangentially of the pitch circle of the gears, 27, 28.

The other housing member 47 may be of substantially similar shape, except that it is not provided with the lateral extension 40 for receiving a spring and ball. Thus the housing member 47 is bell shaped at its open end 48 (Fig. 4), and it tapers downward and has a substantially cylindrical shaft bearing portion 49 at its other end.

The shaft 29 may comprise a metal member having a non-circular lower portion 50, which may be square and of similar shape to the non-circular end portion of the driving member of any socket wrench set. It may be provided with a transverse bore 51 for housing a compression spring 52 and a steel ball 53.

The steel ball is retained in place by peening or spinning inward the metal at 54 adjacent the outer end of the bore 51.

The ball 53 is adapted to engage the wall of a socket complementary to the wrench end 50 so as

to retain the shaft 29 in another wrench fitting or socket, such as the tubular socket 13.

The shaft 29 is also provided with the integral radially extending flange 55 serving as a thrust bearing for engaging a steel thrust washer 56, which in turn is engaged by the annular end 57 of the housing member 47.

The housing member 47 has a cylindrical bore 58 for engaging the cylindrical portion 59 of the shaft 29. The upper threaded portion 60 of the shaft 29 is engaged in a threaded bore of the gear 28 and secured against rotation by a key and key-way, indicated at 61.

Another steel thrust washer 62 is preferably interposed between the gear 28 and the inner thrust surface 63 of the housing 47. The housing members 48 and 47 are thus provided with tapered chambers 64, 65 for receiving and housing the major portion of the gears 27, 28; but the gear teeth 31 project above the outer edge 66 of these housing members.

Thus, when the housing members are brought into engagement with each other, as they would be in the position of Fig. 4, the gears may be completely enclosed, except for the space between the flanges 44, 45, but the teeth 31 of each gear project into the spaces between the teeth of the other gear.

Each housing member 27, 28 is thus rotatably mounted on its shaft 34 or 29. The housing members are preferably secured together for pivotal movement by the flanges 44, 45, previously mentioned, and the flanges 67, 68 carried by the upper housing member 47.

The flange 68 may be provided with a laterally projecting cylindrical lug 69 adapted to be rotatably mounted in the bore 46 of the flange 45. The flange 67 preferably has a cylindrical bore 70 for receiving a trunnion member 71, which is carried by the flange 44.

The trunnion member 71 has a cylindrical portion for engaging in the bore 70, but its outer end is threaded at 72 for receiving the wing nut 73. Thus the trunnion 60 may be placed in the bore 46, and the trunnion 71 in the bore 70; and when the nut 73 is tightened up, its engagement with the outside of the flange 67 will hold the flange 67 against the flange 44 and the flange 68 against the flange 45.

As previously stated, the axis of the bores 46, 70 and the trunnions 71, 60 is preferably substantially tangential to the pitch circle of the two gears. Thus the two housings 27 and 47 may be moved pivotally with respect to each other from the position of Fig. 4 to that of Fig. 2, and to many other positions, while the gears still intermesh with each other.

When the parts are in the position of Fig. 1 or Fig. 2, the rotation of the pole 11 will cause the shaft 24 to rotate, thus rotating the gear 27, which will mesh with the gear 28 and rotate it in the opposite direction.

The two housing members 27, 28 are prevented from rotating by the fact that they are not arranged axially with respect to each other, and thus the shaft 29 may be driven by the handle 11, irrespective of its angular position with respect to the handle.

The wing nut 73 is preferably tightened to place the driven shaft 29 at the proper angle to the driving shaft or the handle 11, and the tool may be used as shown in Fig. 1 for driving nuts or the threaded members on high voltage transmission lines, with perfect safety.

The springs and the ball 42, 43 serve to place

a predetermined friction between the other freely rotatable housing members and the handle 11. Without this friction, if the handle were disposed in horizontal position, the outer end of the wrench would hang down if it were disposed at any angle other than the position where it is in a line with the handle. The friction of the ball 43 prevents the housings from rotating so freely that the wrench end turns down by gravity. Thus, the handle is adapted to hold the handle in any desired position for application to a member to be driven. It is an aid in positioning the socket as it approaches the nut or other threaded member.

Referring to Fig. 4, this is a modification in which the ferrule 20 is replaced by a thrust bearing flange 74, which supports a universal plate 75 of the type adapted to be secured to a pole having a similar plate.

The plate 75 has a centrally located bore 76 communicating with the outer edge of the plate 75 through a slot 77, and the plate is provided with a multiplicity of radially extending and laterally projecting lugs 78 separated by spaces 79.

The bore 76 and the slot 77 are used to pass and receive a threaded bolt carried by the universal flange on a universal pole, which also has similar lugs 78 separated by spaces 79 so that the tool fitting may be applied to any universal pole when constructed as shown in Fig. 4.

It should, however, in most instances be secured with its driving shaft 24 extending axially of the universal pole, as otherwise the universal pole would have to describe an arc in rotating the driving shaft. The special advantage of this embodiment is that the tool may be applied to any universal pole, and it is not necessary for it to be provided with a separate pole of its own.

Referring to Figs. 5 to 8, these views show a modification in which the shaft housings are adapted to lock positively with respect to the two gear driven shafts. The construction of this tool may be exactly the same at the upper end as that described in Figs. 1 to 4, except that the enlargement 40 and the ball and spring 43, 42 are omitted and the housing 80, which is rotatably mounted on the shaft 81, is provided with an integral laterally projecting arm 82, having an aperture 83 located to be engaged by a plunger 84.

The plunger 84 comprises the upper armored end of a round wooden rod 85, which carries a steel or brass sleeve 86 at its upper end. The extreme end may be provided with a substantially frusto-conical point 87, the sleeve 86 being beveled at 88 to be flush with the frust-conical surface so that the end of the plunger 84 is more easily guided into the aperture 83.

The aperture 83 is large enough to embrace the sleeve 86, and when the plunger 84 is in the aperture 83 rotation of the housing 80 on the shaft 81 is prevented. The sleeve 86 may be secured in place by a tight frictional fit and by having a transversely extending metal pin 89 passing through it and the wooden rod 85 and projecting laterally at one or both ends from the sleeve 86 to form a stop member.

The rod 85 is preferably slidably mounted on the wooden pole 11 by means of a pair of guide members 90, 91. These guide members may be similar in shape and construction, but they are longitudinally spaced on the pole, one being preferably located at the upper end adjacent the ferrule 20, and the other being located at the lower end adjacent the end of rod 85. As the length of the pole 11 is increased, a greater number of guide members may be used.

Each guide 90 or 91 may consist of a cast metal collar formed at one side with a radially extending guide portion 92, having a circular bore 93 for slidably supporting the rod 85. At the side opposite the enlargement 92 the collar 90 is preferably provided with a pair of radially extending lugs 94, 95, which are slightly spaced from each other, but which can be drawn together by means of a screw bolt 96 passing through the apertures 97, 98 and tightened by the nut 99.

The parts of the collar intermediate the lugs 94, 95 and the enlargement 92 are substantially cylindrical and substantially complementary to the external cylindrical surface of the wooden pole 11. Thus the collars 90, 91 may be clamped on the wooden pole 11 with their circular bores 93 in alignment with each other and slidably supporting the rod 85.

At its lower end the rod 85 preferably supports a cast metal thumb piece 100. This thumb piece consists of a cast metal member which is formed on the side adjacent the wooden pole 11, with a cylindrically curved surface 101.

The thumb piece may be provided with a centrally located cylindrical bore 102 for receiving the rod 85, with a tight frictional fit, and a metal pin 103 passes through apertures in the rod 85 and thumb piece 100. The upper face 104 of the thumb piece 100 may be flat or of any desired shape, but the lower surface is preferably provided with a concave curvature, indicated by dotted lines at 105, forming a depression for fitting the end of the thumb in the beveled lower surface 106 of the thumb piece.

Thus the fingers of the hand may engage the pole 11, while the end of the thumb conveniently engages the curved surface 105, and the thumb may be so arranged that a pressure on the thumb toward the pole cams the thumb piece 100 upward.

In this motion it is, of course, guided by the cylindrical surface 101, which slidably engages the pole 11, and by the guides 90, 91, which slidably engage the rod 85. The lowermost guide 91 is preferably disposed close enough to the thumb piece 100 so that the light coil spring 107, which is coiled on the rod 85, between this guide and the thumb piece 100, is under an initial state of compression when the pin engages the guide 90.

The pin 89 is so located that the point 87 has its extreme end immediately below the arm 82, when the pin engages the guide 90. Thus the plunger rod 85 is constantly urged to the unlatching position, but it may be engaged in the aperture 83 by pressing on the thumb piece 100 with the thumb.

The device of Figs. 5 to 8 differs also from the one previously described in that the gears are made of cut steel instead of bronze, as they were in the device of Figs. 1 to 4.

I desire it to be understood, however, that the gears may be made of various different materials, the cut steel being preferred from the point of view of strength.

The housing members of the wrench tool of Fig. 5 also differ from the one previously described in that both trunnions are provided with threaded extensions, and a pair of wing nuts 73 may be employed. Steel thrust washers 107 are interposed between the sides of the housings on the trunnions 60 and 71.

Thus both sides or trunnions may be locked to hold the housing in any predetermined angular position by means of the lock nuts 73.

In this embodiment the gears have been more firmly secured on their respective shafts by providing a transverse pin 108 which passes through the shaft 81 and the gear 109.

The bores 110 and 111 are drilled with the gear 109 in place on the shaft 81. The other gear 112 is similarly secured on the shaft 113 by a transverse pin 114, and thus the gears are able to transmit a greater force without breakage than they could when secured merely by a key and key-way.

It will also be noted that the shafts 81 and 83 are longer than the shafts 24 and 29 of the previous embodiment thereby giving a superior bearing surface and reducing any tendency toward binding. The elongated socket sleeve 13 used in the previous embodiment is required wherever nuts have an unusually long travel along a bolt, otherwise a standard socket can be used.

The operation of the tool is as follows: The two housing members 80 and 115 are first secured in the desired angular position so that the wrench end portion 50 will project in the proper direction to engage with a threaded member, on which the tool is to be used, when the operator is holding the handle.

Then the wrench end having been engaged in or on a threaded member, with or without auxiliary socket wrenches, the operator may rotate the handle, causing the shaft 81 to rotate, which rotates the gear 109, which rotates the gear 112 and the shaft 113. During this motion the two housing members 80 and 115 would ordinarily be prevented from rotation by the fact that the shaft 113 extends at an angle to the shaft 81.

The gears and housings are in a way arranged like a system of planetary gears, but the revolution of the housing under these conditions is prevented by the operator, who holds the stick and applies only a rotating force to the stick, while preventing revolution of the stick and housings.

In the embodiment of Figs. 5 to 8, and when it is desired to secure the housing fixedly to the actuating stick, the operator may press upon the thumb piece 109, locking the housing 80 to the stick by means of the plunger 84.

Then the operator may apply a revolutionary force to the end of the shaft 50 by causing the stick 11 to move in such a direction as to revolve about the axis of the shaft 50 to effect a final tightening action. With all parts of the stick locked together in this manner, it is possible to apply a greater force to the wrench than can be applied through the gears alone.

It will thus be observed that I have invented an improved tool for transmission lines, comprising a wrench which is adapted to be used for driving threaded members at any of a multiplicity of different angles.

The operator may have the stick arranged at right angles, for example, to the axis of the threaded member, which is to be driven; and by rotating the pole, such threaded members may be loosened or tightened, or handled as desired, in the same manner as they might be handled on the ground, with ordinary socket wrenches; but with perfect safety, although the transmission line is energized. It is not necessary to de-energize the line, and service need not be interrupted.

The present tool has a provision for locking all of its parts together so that a still more

powerful force can be used than can be applied to the gears alone.

While I have illustrated a preferred embodiment of my invention, many modifications may be made without departing from the spirit of the invention, and I do not wish to be limited to the precise details of construction set forth, but desire to avail myself of all changes within the scope of the appended claims.

10 Having thus described my invention, what I claim as new and desire to secure by Letters Patent of the United States, is:

1. A transmission line tool comprising an elongated insulating handle and a metal tool carried by the end of said handle, said metal tool comprising a pair of bearing members, said bearing members being pivotally secured together, a shaft located in each of said bearing members, one of said shafts being fixedly secured to said pole, and the other having a non-circular formation at its end for service as a wrench, and driving means carried by the adjacent ends of said shafts, whereby the shafts may be driven by said pole irrespective of their angular relation, locking means carried by said pole for locking one of said bearing members to rotate with said pole, and means carried by the bearing member to be engaged by the locking means to lock the bearing member and pole for unitary rotation.

2. A transmission line tool comprising an elongated insulating handle and a metal tool carried by the end of said handle, said metal tool comprising a pair of bearing members, said bearing members being pivotally secured together, a shaft located in each of said bearing members, one of said shafts being fixedly secured to said pole, and the other having a non-circular formation at its end for service as a wrench, and driving means carried by the adjacent ends of said shafts, whereby the shafts may be driven by said pole irrespective of their angular relation, locking means carried by said pole for locking one of said bearing members to rotate with said pole, said locking means comprising a longitudinally movable plunger having an insulating extension slidably mounted on said pole, and means carried by the bearing member to be engaged by the locking means to lock the bearing member and pole for unitary rotation.

3. In a wrench for high tension lines, the combination of an elongated wooden insulating pole with a wrench tool carried by the end of said pole, said wrench tool comprising a metal socket member fixedly secured on said pole, said socket member having an axially extending shaft provided with a gear, a housing surrounding said gear and having a bearing rotatably mounted on said shaft, said housing having a laterally projecting arm, latching means mounted on said pole for engaging said arm and preventing the rotation of said housing, a second housing pivotally mounted on said first housing and having an elongated bearing, a shaft mounted rotatably in said latter bearing and carrying a gear meshing with said first-mentioned gear in a plurality of pivotal positions of said housing, said latter shaft being provided with a non-circular end portion for use with a socket wrench.

4. In a wrench for high tension lines, the combination of an elongated wooden insulating pole with a wrench tool carried by the end of said pole, said wrench tool comprising a metal socket member fixedly secured on said pole, said socket member having an axially extending shaft provided with a gear, a housing surrounding said

gear and having a bearing rotatably mounted on said shaft, said housing having a laterally projecting arm, latching means mounted on said pole for engaging said arm and preventing the rotation of said housing, a second housing pivotally mounted on said first housing and having an elongated bearing, a shaft mounted rotatably in said latter bearing and carrying a gear meshing with said first-mentioned gear in a plurality of pivotal positions of said housing, said latter shaft being provided with a non-circular end portion for use with a socket wrench, said arm having an aperture, and said latching means comprising a rod slidably mounted on said pole.

5. In a wrench for high tension lines, the combination of an elongated wooden insulating pole with a wrench tool carried by the end of said pole, said wrench tool comprising a metal socket member fixedly secured on said pole, said socket member having an axially extending shaft pro-

vided with a gear, a housing surrounding said gear and having a bearing rotatably mounted on said shaft, said housing having a laterally projecting arm, latching means mounted on said pole for engaging said arm and preventing the rotation of said housing, a second housing pivotally mounted on said first housing and having an elongated bearing, a shaft mounted rotatably in said latter bearing and carrying a gear meshing with said first-mentioned gear in a plurality of pivotal positions of said housing, said latter shaft being provided with a non-circular end portion for use with a socket wrench, said arm having an aperture, and said latching means comprising a rod slidably mounted on said pole, said rod being carried by guides on said pole, and having a thumb piece at its lower end and spring means for urging said rod out of engagement with said arm.

20

DAVID C. HUBBARD.
